Primary Examiner—Celia Murphy*(74) Attorney, Agent, or Firm*—Kirkpatrick & Lockhart LLP(57) CLAIMThe ornamental design for a shoe sole, as shown and described.DESCRIPTIONFIG. 1 is a perspective view of a shoe sole showing our new design; and,

FIG. 2 is a bottom plan view thereof.

The broken lines shown in FIGS. 1 and 2 illustrate the environment in which the design resides, and form no part of the claim.1 Claim, 2 Drawing Sheets*FIG. 1
